UNITED STATES PATENT OFFICE.

WILLIAM L. CASPER, OF BROOKLYN, NEW YORK, ASSIGNOR TO WESTERN ELECTRIC COMPANY, INCORPORATED, OF NEW YORK, N. Y., A CORPORATION OF NEW YORK.

TRANSMISSION CIRCUITS.

Application filed May 23, 1922. Serial No. 563,081.

To all whom it may concern:

Be it known that I, WILLIAM L. CASPER, a citizen of the United States of America, residing at Brooklyn, in the county of 5 Kings and State of New York, have invented certain new and useful Improvements in Transmission Circuits, of which the following is a full, clear, concise, and exact description.

10 This invention relates to transmission circuits such as loud speaking amplifier circuits.

One object of this invention is to provide an amplifier and a loud speaking receiver 15 operating without substantial distortion.

Another object is to provide means for overcoming the variable sensitiveness with frequency of a translating device such as a telephone receiver.

20 Another object is to provide a transformer between an incoming line and a receiver such that the distortion of the repeated signals due to the receiver is substantially neutralized by distortion in the 25 transformer.

In accordance with the embodiment of this invention hereinafter described in detail, a telephone receiver is coupled to an incoming line by means of a repeating coil 30 or transformer so designed that the transformer distorts the incoming signals in an opposite sense from the distortion due to the receiver whereby the sounds emitted by the receiver are substantially a faithful representation of the signals received from the 35 line. An electric discharge amplifier of the three-electrode type may be employed between the line and the receiver if desired to increase the volume of the sounds 40 emitted.

It has been found that the combined amplifying horn and receiver, such as are used in loud speaking systems, have a falling sensitiveness for frequencies in the upper 45 range of frequencies of importance in speech. That is,—the amplitude of the vibration of the diaphragm instead of remaining substantially constant over the range of frequencies of importance in 50 speech, tends to decrease at the higher frequencies giving a drooping characteristic.

In accordance with this invention, it has been found that this drooping effect can be substantially neutralized by employing with

the receiver a transformer designed so that 55 for the upper speech frequency range the transmission through the transformer has a rising characteristic compared with the lower and middle speech frequency range. The signals to be translated into sounds 60 therefore have the frequencies of the upper speech range overemphasized by the transformer and underemphasized by the loud speaking receiver whereby the distorting effect of each is substantially neutralized. 65

In my Patents Nos. 1,530,648 and 1,530,649 dated March 24, 1925, have been described various means for giving a transformer a flat transmission characteristic or a rising transmission characteristic. As described 70 therein, the transmission characteristic of a transformer is dependent upon the intensity of the capacity effects between the transformer windings and between the coils of each winding. An inductance device may 75 be connected in series with the transformer windings of such a value as to resonate with the capacity effects to give a transmission characteristic which may vary with the frequency in any desired manner. If the inductance device chosen is of such a value that the resonance peak of the transmission curve is above the frequency range of importance in speech, it follows that the transmission curve of the transformer has a 80 rising slope for the upper speech range. The resonance peak should be adjusted, of course, until the rising characteristic of the transformer substantially offsets or neutralizes the falling characteristic of the associated horn and receiver. Instead of obtaining the resonance effect as above described, it has been found, as also pointed out in the above applications, that the effect of the series inductance element may 85 90 be simulated by adjusting the leakage reactance of the transformer to an appreciable amount, since leakage reactance in a transformer for this purpose is the equivalent of an inductance in series with the primary and secondary windings. 95

In the event that a vacuum tube amplifier is employed between the transformer and the receiver, the capacity effects between the electrodes of the amplifier, especially between the grid and the cathode, should also be taken into consideration in designing the correcting transformer so that the rising 100 105

characteristic curve represents the resultant transmission of the amplifier and the transformer due to the leakage reactance resonating with capacity effects both in the amplifier and the transformer. These capacity effects between the electrodes of a vacuum tube have been discussed in detail in the above noted applications.

Referring to the drawings, Fig. 1 illustrates this invention embodied in a two-stage amplifier working into a loud speaking receiver wherein energy for the amplifiers is obtained from storage batteries; Fig. 2 represents how Fig. 1 may be modified to energize the filaments of the amplifiers from alternating current; Fig. 3 illustrates how both the anode-cathode voltage and heating current may be obtained from an alternating current source of voltage; and Fig. 4 illustrates the transmission curves of a combined loud speaking receiver and horn and of the combined transformer and amplifier circuit of Figs. 1 or 3.

The loud speaking amplifier circuit of Fig. 1 comprises a vacuum tube amplifier 10 working into a push-pull amplifier 11, 12 for receiving and amplifying signals from the incoming line 13, 13 and impressing the amplified signals upon a suitable loud speaking receiver 14 attached to a suitable loud speaking horn 15.

The input circuit of amplifier 10 is connected to line 13 by a transformer 16, the secondary winding of which is provided with a plurality of taps cooperating with a contact arm 17 whereby the effective gain of the amplifiers may be regulated. Contact arm 17 in the position shown in the drawing gives, of course, the maximum gain of the receiving circuit. The output circuit of amplifier 10 is coupled to the input circuits of tubes 11 and 12 by a transformer 18, the secondary winding of which has a midpoint connection to the combined cathodes of tubes 11 and 12, the outside terminals of the secondary winding being connected to the respective grids or control electrodes. The combined output circuits of tubes 11 and 12 are coupled to the loud speaking receiver 14 by a suitable transformer 19. Space current for the tubes 10, 11 and 12 may be obtained by a battery 20 which has its negative terminal connected to the cathodes and its positive terminal connected through primary winding of transformer 18 to the anode of tube 10 and through the two halves of the primary winding of transformer 19 to the respective anodes of tubes 11 and 12. Heating current for the filaments is supplied from a battery 21, which heats the filaments of tube 10 by a path in shunt to a second path containing the filaments of tubes 11 and 12 in parallel. Negative potential for the control electrodes of the three tubes are obtained by

obvious connections to a source of voltage 22.

The type of receiver employed in connection with the amplifiers may, for example, be similar to the structure illustrated and claimed in the United States patent to Egerton on telephone apparatus, No. 1,365,898, issued January 18, 1921.

It has been found in general that the amplitude of vibration of the diaphragm of a loud speaking receiver, such as that shown in the Egerton patent, is not constant with frequency but is variable with frequency especially for the upper speech frequency range. Fig. 4 illustrates by curve 23, the transmission characteristic obtained from a combined loud speaking receiver and amplifying horn wherein the abscissæ represent frequency and the ordinates represent the amplitude of vibration of the diaphragm. The curve as shown in Fig. 4 is plotted on a log scale to an arbitrary base. As shown by curve 23, the combined receiver and horn has a falling sensitiveness for frequencies from 1000 cycles up to the upper range of frequencies of importance in speech, due, in part, to the resonating properties of the diaphragm as well as the combined receiver and horn. This drooping characteristic is objectionable since the sounds emitted by the receiver will not be a faithful copy of the incoming signals since the frequencies in the upper speech range will be underemphasized due to this drooping characteristic. In accordance with this invention, it has been found that this drooping characteristic of the horn and receiver may be substantially neutralized by adjusting the leakage reactances of transformers 16 and 18 so that the transmission characteristic curve of the amplifier and transformer circuit has a rising slope for the upper speech frequency range as shown in curve 24 of Fig. 4, the abscissæ for which represent frequency and the ordinates represent miles gain, both plotted on a log scale.

When the transformers employed are of the two-mesh type, with the windings wound on the common limb of the two meshes, a convenient method for making the leakage reactance appreciable is to reduce the cross section of the common limb to a considerable extent over the cross section it should have in ordinary transformer practice. For example, appreciable leakage reactance may be obtained by making the cross section of the center common limb, two-thirds of the average cross section of the rest of one of the meshes added to the average cross section of the rest of the second mesh. This has been described and claimed in detail in the copending United States patent to F. E. Field, No. 1,507,994 dated September 9, 1924. The leakage reactances of the transformers act as inductance elements in series with the primary and secondary windings of the transformers and these equivalent inductance

elements resonate with the internal capacity effects of the transformers and the internal capacity effects between the electrodes of the amplifiers to give a tuned circuit which may 5 have its resonance peak at a frequency above the frequency range of importance in speech. If the leakage reactances are adjusted to give the resonance peak above the speech frequency range, it follows that the resultant 10 transmission curve for the combined amplifiers and transformers will have a rising slope from the middle speech frequency range to the upper speech frequency limit. The various elements of the amplifier circuit 15 may be adjusted to give this slope the proper characteristic and rising characteristic substantially opposite and equal to the falling characteristic of the combined horn and receiver. With such an arrangement therefore 20 the combined transformers and amplifiers will overemphasize the upper speech frequency range an amount substantially equal and opposite to the underemphasizing of the upper speech range by the horn and receiver. 25 The result of the combination, is therefore, to give a greatly improved transmission especially for the upper speech frequency range, and the sounds emitted by the receiver will be a substantially faithful copy of the 30 signals received from the incoming line 13. In one case the value of this curve for 1000 cycles represented fifty miles gain, while the value of the curve for 5000 cycles represented fifty-six miles gain.

35 As described in the Arnold Patent No. 1,349,252 of August 10, 1920, each of the amplifiers 11 and 12 should be arranged so that they work into an output impedance substantially equal to their internal impedance. If desired, a ground connection 40 may be provided for the cathodes so that the cathodes may be substantially grounded whereby singing is prevented.

This invention, of course, is not limited to 45 an amplifier arrangement in which the heating current for the filaments is obtained from a battery since the energizing voltage for the tubes may be obtained by various arrangements. Fig. 2, for example, shows an 50 alternative arrangement in which the cathodes may be connected to terminals 26 and 27 and heated by alternating current obtained through a transformer 28, the primary winding of which is in circuit with 55 an alternating current source 29. In order to prevent the low frequency hum of the generator 29 from being impressed upon receiver 14, the anode and grid connections through batteries 20 and 22 should be taken 60 from the midpoint of the secondary winding of transformer 28.

Fig. 3 is an alternative arrangement in 65 which the anode-cathode voltage for the tubes 10, 11 and 12 is obtained by rectifying alternating current from a suitable gen-

erator 34. As shown in this figure, generator 34 is connected to the amplifiers through a transformer 35. The midpoint of the secondary winding of transformer 35 by lead 36 is connected to the anodes of tubes 10, 11 70 and 12, one end of the secondary winding being connected to the cathodes through a two-electrode rectifier 37 and the other end being connected through a two-electrode rectifier 38 to the cathodes. The rectified voltage obtained through tubes 37 and 38 may be smoothed out by inserting between the amplifier tubes 10, 11 and 12 and the rectifiers a Campbell wave filter 39 of as many sections as desired. This filter should be 75 designed to pass only the direct current component of the rectified voltage. The manner in which the filter should be designed is described in detail in the United States patent to Campbell, No. 1,227,113 of May 22, 80 1917. Heating current for the cathodes of tubes 10, 11 and 12 is obtained in Fig. 3 by connections to an alternating current source 40 which may be similarly connected as in Fig. 2. In addition to connecting the various grids and anodes of the amplifier tubes to the midpoint 41 of the secondary winding of the transformer 42, it may be found advisable to also connect thereto by a lead 43, 85 one side of the secondary winding of transformer 19 which is in circuit with the receiver 14. This connection aids in eliminating the hum in the receiver due to heating the filaments by alternating current.

The above described loud speaking amplifier circuit is of general utility and capable of wide use in the art. It is particularly suitable, for example, to be employed in the amplification of detected radio frequency signals in which case incoming line 13, 13 90 may be suitably connected to the output circuit of a high frequency detector. Various modifications may be made in the above described circuit without departing in any wise 95 from the spirit of the invention as defined in the appended claims.

The invention claimed is:

1. In combination, a loud speaking receiver having a falling characteristic over a given range of speech frequencies, and a transformer in circuit therewith having a rising transmission characteristic over said range.
2. In combination, a loud speaking receiver having a varying transmission characteristic over a given range of impressed frequencies, and a combined amplifier and transformer arrangement in circuit therewith having a transmission characteristic over said range varying in an opposite manner.
3. In combination, a combined loud speaking horn and receiver having a falling sensitivity over a range of speech frequencies, and a combined transformer and amplifier 130

arrangement in circuit with said receiver, and having a rising transmission characteristic over said range.

4. In combination, means having a varying sensitiveness for translating electric waves into sound waves, means comprising a transformer, a plurality of windings for said transformer, said second means having a rising transmission characteristic for a given range of frequencies for neutralizing to a substantial extent the varying sensitiveness of said first-mentioned means over said range.

15 5. In combination, means having distortion-producing characteristics for translating electric waves into sound waves of the speech frequency range, an incoming line, and means including a transformer connecting said line with said first means, and having a transmission characteristic resonating at a frequency above the speech range for neutralizing the distortion produced by said first means.

25 6. In combination, means having distortion-producing characteristics for translation.

ing electric waves into sound waves, and means comprising a transformer of high leakage reactance to give a rising characteristic for overcoming the distortion produced by said first means.

7. In combination, means having distortion-producing characteristics for translating electric waves into energy of another character, and means comprising a transformer of high leakage reactance to give a 35 rising characteristic for overcoming the distortion produced by said first means.

8. In combination, an incoming line, means for translating electric waves from said line into sound waves, said means having a transmission characteristic varying with frequency, amplifying means and a transformer between said line and said first means, said amplifying means and said transformer having a transmission characteristic varying in the opposite sense to the variation of said first means. 40 45

In witness whereof, I hereunto subscribe
my name this 22nd day of May, A. D. 1922.

WILLIAM L. CASPER.
